CLAIM

The ornamental design for a floral arrangement tool, as shown and described.

DESCRIPTION

FIG. 1 is a perspective view of a floral arrangement tool, showing our new design with a U-shaped clamshell portion in a folded configuration;

FIG. 2 is an exploded perspective view thereof;

FIG. 3 is an exploded front elevational view of FIG. 2;

FIG. 4 is an exploded rear elevational view of FIG. 2;

FIG. 5 is an exploded left-side elevational view of FIG. 2, the right-side elevational view being a mirror image thereof;

FIG. 6 is an exploded top plan view of FIG. 2;

FIG. 7 is an exploded bottom plan view of FIG. 2;

FIG. 8 is an exploded top perspective view thereof, showing the U-shaped clamshell portion in a flat configuration; and,

FIG. 9 is an exploded bottom perspective view of FIG. 8. The broken lines in FIG. 1 showing a floral arrangement and a person depict environmental matter that forms no part of the claimed design. The remaining broken lines in the figures depict portions of the floral arrangement tool that form no part of the claimed design.
